DETACHABLE COUPLING

Alan P. Buffington, Philadelphia, Pa., assignor to
 Philco Corporation, Philadelphia, Pa., a corpora-
 tion of Pennsylvania

Application August 22, 1946, Serial No. 692,298

8 Claims. (Cl. 287—53)

1

The invention hereinafter described and claimed relates to detachable coupling means and, more particularly, is concerned with control knob and shaft assemblies of the type in which a knob is normally adapted for positive driving engagement with a shaft and may be readily released and removed therefrom.

In certain types of apparatus, particularly in radio or other electrical apparatus, there are utilized control shafts which project outwardly from a housing or cabinet into engagement with a suitable knob or other operating element, to be driven thereby. Manufacture and assembly of such apparatus, as well as repair and replacement of parts thereof, can be greatly facilitated by the use of knob and shaft devices of such a nature that assembly may be made merely by fitting the knob over the free end of the shaft, without resort to guideways, set screws or the like. Although such devices have been devised, they have frequently been subject to difficulties and disadvantages, in that it is necessary to achieve secure retention of the knob upon the shaft and positive driving engagement between these elements, while at the same time permitting ready dis-association of the two parts.

The present invention has as an object the provision of a novel and improved knob and shaft assembly, of such a nature that relative coupling and uncoupling thereof may be accomplished in the simplest possible manner.

It is a further object of this invention to provide a knob which may be readily and inexpensively manufactured, as by a molding operation, which knob includes an element effective to automatically establish positive driving connection with an associated shaft, the connection being such that while inadvertent disassociation of the knob from the shaft is not possible during normal usage, the knob may be easily removed by effecting a special rotary manipulation thereof.

The invention also has as an object the provision of a knob and shaft assembly in which no tools are required during either mounting or removal of the knob.

The manner in which the foregoing objects and advantages are realized will be best understood by reference to the following specification, considered in the light of the accompanying drawing, in which:

Figure 1 is a side elevational view of a knob and shaft assembly constructed in accordance with the present invention, a portion of the knob being broken away to facilitate illustration.

2

Figure 2 is a sectional illustration, on an enlarged scale, the view being taken as indicated by the line 2—2 of Figure 1.

Figure 3 is a view similar to Figure 2, and illustrating the relative angular disposition of the knob and shaft during removal of the knob; and,

Figure 4 is a view in perspective of the shaft and the knob retaining element.

Making more detailed reference to the drawings, there is shown in Figure 1, and designated generally by the reference character 5, a shaft of the type utilized to control variable tuning condensers, or like apparatus. As shown, the shaft is circular in cross section, and has a portion adjacent its free end cut away to provide a plane surface 6 extending axially of said shaft, and adapted to cooperate with a knob retaining element or spring leaf 7, in a manner presently to be described. The knob, designated at 8, comprises a head portion 9, which is manipulated by the operator during adjustments of the shaft 5, and a collar portion 10 having an internal diameter of a size to fit over said shaft 5 in the region of said plane surface 6.

In particular accordance with the present invention, the aforementioned retaining element 7 comprises a relatively stiff resilient member, of steel or like material, having one end 11 fixedly secured within the collar 10 and a blade portion 12 normally extending backwardly within the knob, at an angle of approximately 45 degrees with respect to the shaft. This angle is such that the knob may be readily slipped over the end of the shaft, with the blade 12 sliding across the "flat" provided by the surface 6. The blade of the retaining element is relatively thin and, accordingly, any attempt to pull the knob off the shaft causes the free edge of the blade (represented at 13 in Figures 2 and 4), and particularly the corner portion 14, to dig into the surface 6 and thereby prevent removal of the knob.

As best appears in Figures 2 and 4, the blade portion 12 bears upon the surface 6 through a considerable distance and will, therefore, under the influence of the resilient pressure of the blade, prevent relative rotational movement of the knob and shaft under all normal conditions of operation. This extended bearing contact also minimizes the alignment required when the knob is being mounted, since the knob automatically centers itself during the mounting operation, seeking an angular position in which the major portion of the free edge of the blade is in contact with the surface 6.

Removal of the knob is accomplished by rotating the shaft in a clockwise direction to the end of its travel (if the apparatus necessitates it, a special stop may be provided) and thereafter continuing the rotational movement a very short distance, as represented in Figure 3, until an upwardly curled low friction surface-portion 15 of the retaining element or blade bears upon the surface 6. While such small additional rotation of the knob may be readily effected, it will be understood that such movement is effected against the resilience of the blade 12, which resilience should be sufficient to insure that the knob will not be rotated to this position, inadvertently. When the position illustrated in Figure 3 has been reached, the relatively sharp edge portion 13 no longer bears against surface 6—only the rounded surface 15 making contact with the shaft—and the knob may then be slipped from the shaft, sufficient torque being maintained to retain the portion 15 in contact with said surface 6. It will be appreciated that the portion 15 may take other forms, the important factor being the relatively low friction of the surface.

From the foregoing description, it will be understood that the present invention provides a novel and advantageous knob and shaft assembly, in which mounting and removal of the knob may be effected in an extremely simple manner.

While a preferred embodiment has been illustrated in the drawings and described in the specification, it will be understood that the invention is susceptible of certain modifications without departing from the essential spirit thereof. For example, the retaining element or blade 7 might be secured to the shaft 5, and a suitable "flatted" portion be provided in the collar 10 against which the free end of the resilient blade would bear. However, it will be understood that such changes and modifications are contemplated as may come within the terms of the appended claims.

I claim:

1. In a disconnectable coupling assembly, a pair of disconnectable elements, a coupling member secured to one of said elements and having a relatively high friction surface-portion normally bearing resiliently against the other of said elements and preventing movements tending to disconnect said elements, and low friction means disposed out of contact with said other element when said high friction surface portion is in contact therewith, said elements being relatively rotatable through a small angle against the resilient pressure aforesaid, such rotation acting both to move said high friction surface portion out of contact with the said other element and to bring said low friction means into contact therewith, whereby to provide for disconnection movements of said elements.

2. In a disconnectable coupling assembly, a pair of disconnectable elements, a coupling member secured to one of said elements and having a relatively sharp edge normally bearing resiliently against the other of said elements, said edge normally impinging against said other element at such an angle as to prevent movements tending to disconnect said elements, and low friction means disposed out of contact with said other element when such sharp edge is in contact therewith, and said elements being relatively rotatable through a small angle against the resilient pressure of said member, such rotation acting both to move said edge out of contact with the said other element and to bring said low friction means into contact

therewith, whereby to provide for sliding of said member across said other element and disconnection of the assembly.

3. A disconnectable coupling assembly, comprising a pair of disconnectable elements, and a spring leaf secured to one of said elements and having a relatively sharp edge normally bearing resiliently against the other of said elements, said edge normally impinging against said other element at such an angle as to prevent movements tending to disconnect said elements, said spring leaf further having a relatively smooth rounded surface disposed out of contact with said other element when said sharp edge is in contact therewith, and said elements being relatively rotatable through a small angle against the resilient pressure of said spring leaf, such rotation acting both to move said edge out of contact with said other element and to bring said rounded surface into contact therewith, whereby to provide for sliding of said leaf across said other element and disconnection of the assembly.

4. In a control knob adapted for disconnectable association with a shaft, to be driven thereby, a portion adapted to surround an end of the shaft, and coupling means secured within said portion and disposed to bear resiliently against the shaft inserted within said portion and resist relative rotation between the knob and shaft, said means further being effective to create a high frictional resistance to relative axial movement between said knob and the shaft whereby to prevent withdrawal of said knob from the shaft under normal conditions of operation, said means further having a low friction surface-portion so located as normally to be disposed out of contact with the shaft, said knob being adapted for rotation through a small angle with respect to the associated shaft against the resilient pressure of said means to substantially eliminate said high frictional resistance and to bring said low friction surface-portion into contact with the shaft, whereby to provide for sliding of said means along the shaft and removal of the knob therefrom.

5. In a control knob adapted for disconnectable association with a shaft to be driven thereby, a portion adapted to surround an end of the shaft, and a coupling spring leaf secured within said portion and having an edge adapted to bear resiliently against the shaft and resist relative rotation between the knob and shaft, said edge being relatively sharp and so disposed as to impinge against the shaft at such an angle as to prevent withdrawal of the knob from the shaft under normal conditions of operation, said spring leaf further having a rounded surface so located as to be disposed out of contact with the shaft when said edge is in bearing engagement therewith, said knob being adapted for rotation through a small angle with respect to the associated shaft against the resilient pressure of said spring leaf both to move said edge out of contact with the shaft and to bring said rounded surface into contact therewith, whereby to provide for sliding of said spring leaf along the shaft and removal of the knob therefrom.

6. In a control knob adapted for disconnectable association with a shaft to be driven thereby, an interior wall structure defining an open-ended shaft-receiving portion, and a resilient member having one end carried by said wall structure, and another end extending from said wall structure laterally into said shaft-receiving portion and rearwardly with respect to the open end thereof,

said other end being provided with both a relatively sharp edge adapted to bear resiliently against the shaft and with a low friction surface-portion so located with respect to said sharp edge as to be disposed out of contact with the shaft when said sharp edge is in bearing engagement therewith, the construction being such that slight rotation of the knob with respect to the shaft will move said sharp edge out of contact with the shaft and bring said low friction surface-portion into contact therewith.

7. In a disconnectable knob and shaft assembly, a knob provided with interior wall structure defining an open-ended shaft-receiving portion, a shaft having an end portion disposed within said shaft-receiving portion, said end portion having an axial cut providing a substantially flat surface in general parallelism with the axis of the shaft and spaced from the said interior wall structure, and a spring leaf carried by said wall structure and extending therefrom laterally into said shaft-receiving portion and rearwardly with respect to the open end thereof, the free end of said leaf being provided with both a relatively sharp edge bearing resiliently against the said flat surface and with a low friction surface-portion so located with respect to said sharp edge as to be disposed out of contact with said flat surface when said sharp edge is in bearing engagement therewith, said knob and shaft being relatively rotatable through a small angle against the resilient pres-

sure of said leaf, such rotation acting both to move said sharp edge out of contact with the said flat surface and to bring said low friction surface-portion into contact therewith.

- 5 8. In a disconnectable coupling assembly, a pair of disconnectable elements, a coupling member interposed between said elements and having a relatively high friction surface-portion normally bearing resiliently against one of said elements and preventing movements tending to disconnect said elements, and low friction means disposed out of contact with the said one element when said high friction surface-portion is in contact therewith, said elements being relatively rotatable through a small angle against the resilient pressure aforesaid, such rotation acting both to move said high friction surface-portion out of contact with the said one element and to bring said low friction means into contact therewith, whereby 10 to provide for disconnection movements of said elements.
